UNITED STATES PATENT OFFICE.

EDWARD B. ENTWISLE, OF JOHNSTOWN, PENNSYLVANIA, ASSIGNOR, BY
MESNE ASSIGNMENTS, TO THE JOHNSON COMPANY, OF PENNSYLVANIA.

RAILWAY-SWITCH.

SPECIFICATION forming part of Letters Patent No. 508,095, dated November 7, 1893.

Application filed January 26, 1893. Serial No. 459,903. (No model.)

To all whom it may concern:

Be it known that I, EDWARD B. ENTWISLE, a citizen of the United States, residing at Johnstown, in the county of Cambria, State of Pennsylvania, have invented a new and useful Improvement in Railway-Switches, of which the following is a true and exact description, due reference being had to the accompanying drawings.

- 5 10 This invention relates to an improvement in that class of railroad-spring switches, in which the spring rail or tongue is held in position by a coiled spring. In a switch of this kind the spring and its necessary covering projecting out from the side of the rail offer to the wheel of a passing wagon an obstruction over which it must go, causing a jolt in the wagon and bringing a heavy strain on the spring box. In a road that is well kept and 15 20 when the rails do not project much above the surface of the road this jar will not be so appreciable, but in a poorly kept road which has been permitted to settle below the level of the rails and possibly has a deep rut along 25 the track the jar will be much greater.

The object of my invention is to provide a covering for the spring which shall offer the least obstruction in the roadway and also be so constructed as to support any weight that 30 35 may be passed over it and bring the least strain on the fastenings which secure it to the switch rails.

In the drawings: Figure 1 represents a general plan of such a switch. Fig. 2 shows a larger plan of the switch box and its fastenings to the rail. Fig. 3 is a side view of Fig. 2, and Fig. 4 is a section of Fig. 2 on the line X—X. Fig. 5 is an end view of Fig. 2 and Fig. 6 is a section of Fig. 2 on the line Y—Y. 40 Figs. 7 and 8 show the construction of the box. It will be seen that the box or case c is se-

cured to the rail t by the two bolts b passing through the lug on each end of the case c. The rod r is securely fastened to the spring rail or tongue t' as by a nut and 45 passes through the web of rail t and through the spring s. By means of a nut n on the end of the rod r any desired tension may be put on the spring s to hold the two rails t and t' together. The plate p in the end of 50 the box is merely to keep out the dirt, the open end also allowing the easy removal of the spring s and rod r without disturbing the other parts. I construct the box as shown, of a triangular section having a broad base 55 and the top rising gradually from each side, thus forming an easy rise for a wheel passing over it. On account of the broad base I am enabled to support the box firmly in the road bed or a tie may be placed under the rail here 60 so that the box may rest directly upon it. Or the box may be formed having the top flat in the center and an incline on each end for the purpose of forming an easy rise for a wheel.

Having described my invention, what I 65 claim, and desire to protect by Letters Patent, is—

- 1. In a spring switch, a box or receptacle for the spring formed with a removable side for inserting and access to spring. 70
  - 2. In a spring switch, a box or receptacle for the spring having the top provided with two inclines substantially as described.
  - 3. In a spring switch, a box or receptacle for the spring having a broad base and the 75 top sloping from the middle toward the sides.
- In testimony whereof I have affixed my signature in presence of two witnesses.

EDWARD B. ENTWISLE.
